UNITED STATES PATENT OFFICE

2,487,817

METHOD FOR PRODUCING COORDINATE SCREENS FOR CATHODE-RAY OSCILLOSCOPES

William Lubin, United States Navy

Application June 7, 1945, Serial No. 598,183

2 Claims. (Cl. 18—56)

(Granted under the act of March 3, 1883, as amended April 30, 1928; 370 O. G. 757)

1

This invention relates in general to a method for forming an auxiliary conforming screen for cathode-ray tube.

An oscilloscope tube is essentially of the same exterior construction as the conventional cathode ray tube. These tubes comprise a highly evacuated envelope, usually of glass, having at one end integrally associated with the envelope a special translucent screen which fluoresces when a beam of electrons is directed thereonto. The end comprising the translucent screen is conventionally of convex shape to impart strength to the tube.

In an oscilloscope the electron beam is so deflected under varying conditions that a pattern is formed upon the fluorescent screen of the tube. It is frequently desirable to determine exactly the dimensions of the pattern upon the fluorescent screen. For this purpose transparent auxiliary screens having co-ordinate lines inscribed thereon have been placed in front of the oscilloscope screen. The auxiliary screen is often merely a flat window in an oscilloscope instrument panel having a coordinate system inscribed thereon and behind which the oscilloscope tube is installed. In using such an auxiliary screen parallax error is introduced due to the fact that the screen or window upon which the coordinate lines are inscribed and the coordinate lines themselves are not of the same contour as the fluorescent screen upon which the image occurs.

An object of this invention is to provide a method of producing an oscilloscope screen having a concave surface with coordinate lines thereon.

Further objects and advantages of this invention, as well as its construction, arrangement and operation, will be apparent from the following description and claims in connection with the accompanying drawing in which

Fig. 1 is a fragmentary side elevation representing the end of a conventional cathode-ray oscilloscope tube,

Fig. 2 is a sectional side elevation of a coordinate screen embodying this invention, and

Fig. 3 is a fragmentary front elevation of an oscilloscope instrument panel showing the coordinate screen of this invention installed therein.

Fig. 1 shows the end of a conventional cathode ray oscilloscope tube, generally designated as 11, having a fluorescent screen 12 of a convex shape.

Fig. 2 shows an auxiliary screen embodying this invention, consisting of a plate of transparent material, such as clear, transparent, methacrylate resin called "Lucite," generally design-

nated as 13, one surface 14 of which is of such concavity as substantially to fit the convex end of the fluorescent screen 12. Upon the concave surface 14 is a system of coordinate lines 15. These lines are scribed or otherwise cut or impressed into the surface of the material and are filled with coloring matter such as India ink or other suitable opaque substance. It is essential that the coordinate system be curved to the same contour as the concave surface 14; straight lines projected onto the curved surface would introduce the same parallax error as would be introduced in using a flat plate. The coordinate lines 15 are therefore placed upon the curved surface 14 of the screen 13 in such a manner that both vertical and horizontal lines correspond in contour substantially to arcs of the concave surface.

The concave screen 13 may be placed in a panel board of an oscilloscope instrument as in Fig. 3, wherein 16 indicates the panel board, and 17 and 18 represent retaining ring and gasket respectively. The cathode ray oscilloscope 11 is installed behind the panel board 16 so that its end 12 fits snugly in the concave portion 14 of the screen 13.

This invention resides in the method of producing the coordinate screen described above. According to this method a system of coordinate lines is scribed or otherwise cut or impressed upon a flat surface of a plate of Lucite or other transparent material capable of being molded. These lines are filled with suitable coloring matter so as to make them stand out clearly and sharply. The plate is then molded in such a manner as to make the former flat surface containing the coordinate system conform in contour to the end of the tube of the cathode-ray oscilloscope so that the plate may be placed upon the end of the tube with the lined surface contacting the tube at substantially all points. In this manner the coordinate lines are curved in exactly the same manner as the fluorescent screen and the image upon the screen may be measured by reference to these lines without error.

Optionally the coloring matter may be applied to the scribed lines after the plate is molded.

The above described method is readily adaptable to many uses wherein it is desired to place a pattern upon a molded or fashioned object.

It is to be understood that various modifications and changes may be made in this invention without departing from the spirit and scope thereof as set forth in the appended claims.

The invention described herein may be manufactured and used by or for the Government of

the United States of America for governmental purposes without the payment of any royalties thereon or therefor.

What is claimed is:

1. The method of producing a coordinate screen for cathode-ray oscilloscopes comprising inscribing one surface of a plate of transparent moldable material with a system of coordinate lines, and molding said surface of said inscribed plate to conform to the end contour of the tube of the cathode-ray oscilloscope whereby the lines of said system are curved in accordance with end contour of the tube and whereby, in turn, readings taken on said system of lines avoid parallax.

2. The method of producing a parallax-less coordinate screen for the arcuate end of a tube of a cathode-ray oscilloscope, said method comprising inscribing a system of coordinate lines upon a flat surface of transparent moldable material and thereafter molding said surface to conform to such arcuate end whereby a curvature is given to said lines and whereby, in turn, readings, taken on

said lines having said curvature, are without parallax.

WILLIAM LUBIN.
